UNITED STATES PATENT OFFICE.

JONATHAN H. COOPER, OF MARSHALL, TEXAS.

WATCH-CASE BOW.

SPECIFICATION forming part of Letters Patent No. 399,840, dated March 19, 1889.

Application filed August 25, 1888. Serial No. 283,707. (No model.)

To all whom it may concern:

Be it known that I, JONATHAN H. COOPER, of Marshall, in the county of Harrison and State of Texas, have invented certain new and useful Improvements in Watch-Bow Fastenings; and I do hereby declare that the following is a full, clear, and exact description of the invention, which will enable others skilled in the art to which it appertains to make and use the same, reference being had to the accompanying drawings and to the letters of reference marked thereon, which form part of this specification.

My invention relates to an improvement in fastenings for bows of watch-cases.

Heretofore watch-bows have been fastened to the pendants in various manners. For instance, the ends of the bow have been provided with heads fastened to the bow by being secured in holes in the sides of the same, the two ends of the bow extending through holes in opposite sides of the pendant, so that the heads on said ends will extend into the interior of the pendant, and are held in this position and prevented from springing back by a locking-plate consisting of a slotted tube or segment of a tube slipped into the inside of the pendant with its slots embracing the contracted portions of the bow ends behind the heads, so that said heads project inwardly beyond the locking-plate.

It is also well known that rotating stems have been fastened in watch-pendants to allow rotatory movement and prevent longitudinal play of the stem by one or more pins or screws extending through the pendant into an annular groove in the stem.

The object of my invention is to provide a strong, exceedingly cheap, simple, and durable manner of securing the bow to the pendant of a watch, and one that will avoid and overcome all the numerous disadvantages of the old devices heretofore in use, and whereby the bow is firmly yet loosely secured to the pendant, but can be readily removed from the same without removing the stem of the watch or interfering with the interior of the pendant, and also one that can be used with any kind of a watch, whether the case is a key or stem lever or pendant set.

With these ends in view my invention con-

sists in the combination of a watch-pendant, a pair of radially-projecting bosses or annular flanges secured to or formed with the pendant and located diametrically opposite on the periphery of the same, a watch-bow the ends of which are provided with annular grooves and loosely fit in said bosses, so that the grooves will also be located in the same, said bosses being provided with radial threaded openings, and set-screws extending from the periphery of the bosses through said openings removably into the annular grooves of the bow ends, whereby the bow is firmly yet loosely secured to the pendant.

Figure 1 is an elevation of a watch-case, bow, and pendant. Fig. 2 is a detail view of the bow, dotted lines representing the pendant. Fig. 3 is a view of a bow and pendant, the pendant and a portion of the bow being in section. Fig. 4 is a cross-section of the pendant on line $x-x$, Fig. 3, the bow being turned to one side and shown in section. Fig. 5 is a detail longitudinal section of the pendant, showing the annular bosses or flanges formed on the same.

In the drawings, the reference-letter *a* indicates any suitable watch-case, preferably inclosing a stem-winding or keyless watch and provided with a pendant, *b*.

A pair of annular flanges or bosses, *c c'*, are formed upon diametrically-opposite points on the periphery of the pendant and extending radially from the same in opposite directions, and said bosses are formed of a suitable diameter and length and of strong material. After the bosses have been formed apertures are drilled or otherwise formed through the pendant, so that the bosses will surround the same, and the apertures thus will be diametrically opposite.

d indicates a watch-bow of any suitable construction provided at its opposite ends with annular grooves *e e'*, located a suitable distance from the extreme ends, as shown.

A screw-threaded hole is tapped or otherwise formed radially through the side of one boss or flange, *c*, to receive a set-screw, *f*, adapted to project into the interior of the boss. A similar screw-threaded hole is formed through boss *c'*, although preferably upon the side diametrically opposite the side of the

boss *c* in which screw *f* is located, and in said last-mentioned hole a screw, *f'*, is located.

In assembling the parts, one end of the bow *d* is placed in a boss, preferably extending 5 through the same into the pendant, and the set-screw in that boss is then screwed so as to project into the annular groove in the end of the bow. The opposite end of the bow is then sprung into the opposite boss and the screw 10 in that boss screwed into the annular groove. The bow is thus secured to the pendant and yet allowed to swing upon the same as a pivot, and can be removed by unscrewing the set-screws.

15 It is clearly evident that my fastening differs from the old fastening, before described, in many essential particulars, in view of the fact that said old fastening can only be used on hunting-case or open-face lever-set watches, 20 and cannot be used for pendant-set cases, because of the locking-plate, and as the ends of the bow necessarily project beyond the inner faces of said plate and on account of the necessity of cutting screw-threads inside the 25 pendant to screw in the setting device. This fact is very important, as a large number of the watches now used are pendant set; and, further, where this old fastening is used the bow cannot be detached without removing 30 the stem and getting into the interior of the

pendant; hence they do not and could not use flanges or bosses, which are essential in my device, and it is by reason of these flanges that the bow is secured to the exterior of the pendant, and can be removed or replaced, or 35 placed upon any watch, without interfering in any way with the interior of the pendant.

What I claim is—

The combination of a watch-pendant, a pair of radially - projecting annular bosses or 40 flanges secured to or formed with the pendant and located diametrically opposite on the periphery of the same, a watch-bow having its ends provided with annular grooves and loosely fitting in said bosses, so that the grooves 45 will also be located in the same, said bosses being provided with radial threaded openings, and set-screws extending from the periphery of the bosses through said openings removably into the annular grooves of the bow ends, 50 for the purpose and in the manner substantially as described.

In testimony that I claim the foregoing as my own I affix my signature in presence of two witnesses.

J. H. COOPER.
